GRINDING APPARATUS

Kurt Zwick, Munich, Germany, assignor to Feinmechanik G.m.b.H., Weilheim, Germany, a company of Germany

Filed Apr. 10, 1963, Ser. No. 272,065

Claims priority, application Germany Apr. 25, 1962
7 Claims. (Cl. 51—273)

This invention relates to grinding apparatus, and more particularly to the type of grinding apparatus in which a grinding wheel or like movable member of abrasive material is enclosed in the cavity of a casing connected to dust collecting equipment and provided with a minimum number of apertures for access of the work piece to be ground and of a grinding wheel dressing tool.

As is well known, abrasive working of a workpiece creates dust, and even more dust is usually formed when the grinding wheel is dressed. To protect workers from the dust, it is conventional to enclose grinding wheels in a casing as far as is consistent with proper operation, and to exhaust air and dust from the casing. It is not usually convenient to pass a workpiece to be ground and a grinding wheel dressing tool through the same opening in the casing because of the different requirements of the two grinding and wheel dressing operations. It has heretofore been conventional for this reason to provide a grinding wheel casing with two circumferentially spaced openings suitably located for passage of a work piece and of a dressing tool.

It is a disadvantage of the known arrangement that dust is free to escape through the opening intended for the dressing tool during grinding while the other opening is at least partly obstructed by the work piece and the hand holding the work piece. Conversely, dust escapes during wheel dressing through the opening intended for the work piece. If the suction of the exhaust equipment is sufficiently increased to minimize dust escape through the unused opening, much air is drawn into the casing through the unobstructed opening, and the exhaust equipment is operated at very low efficiency.

It is the object of the invention to provide a grinding apparatus of the type described in which the exhaust system may be operated efficiently and economically without permitting the escape of dust from the two spaced apertures available in the casing for insertion of a work piece and of a dressing tool respectively.

Other objects and features of the invention will become apparent to those skilled in the art as the disclosure is made in the following detailed description of a preferred embodiment of the invention as illustrated in the accompanying sheet of drawing in which:

FIG. 1 is a fragmentary front-elevational view of a grinding apparatus of the invention;

FIG. 2 shows the apparatus of FIG. 1 in fragmentary side elevation;

FIG. 3 illustrates the apparatus of FIG. 1 in side-elevational section on the line III—III;

FIG. 4 shows the apparatus of FIG. 1 in a different operational position; and

FIG. 5 shows the apparatus of FIG. 4 in a view corresponding to FIG. 3.

Referring now to the drawing in detail, and initially to FIGS. 1 to 3, there is shown a casing 12 in which a cup shaped grinding wheel 10 is rotatably mounted on a drive shaft 11. The cavity of the casing 12 in which the wheel 10 normally rotates is axially closed by a releasably attached cover 14. An exhaust aperture 15 in the casing cavity communicates with the suction duct 13 of an exhaust system which also includes a non-illustrated dust collecting chamber and vacuum pump, as is conventional.

In the position of the grinding apparatus illustrated in

2

FIGS. 1 and 2, a portion of the grinding wheel 10 is exposed to the atmosphere and accessible to a tool bit 22 for grinding of the latter on a radial face of the wheel 10. To permit entry of the tool bit 22 into the casing cavity, the circumferential cylindrical wall of the casing 12 has an aperture 16 extending circumferentially over an arc of about 130°, and the cover 14 has a peripheral cut-out 18 adjacent the aperture 16 and of similar circumferential length. A guide member 17 on the casing 12 guides the tool bit toward the wheel 10. The cover 14 further has an elongated slot 20 which is arcuate about the axis of a pivot pin 21 which is rotatable and axial slidable in the casing 12. The axis of rotation of the pin 21 is parallel to that of the drive shaft 11.

The pin 21 is integral with a radial arm 24 which constitutes a dressing tool carrier. The dressing tool is not shown in the drawing. It may be of the type disclosed in my copending, simultaneously filed application Serial No. 272,064, and consists of an elongated rod from which a diamond projects in a longitudinal direction. The rod may be inserted in the bore 23 of the arm 24, and secured therein by means of a set screw 25.

A cup shaped closure member 26 is rotatably mounted on the cover 14 coaxially with the grinding wheel 10. The closure member consists of a bottom portion 28 extending in a radial plane, and of a substantially cylindrical wall portion 30. The open side of the closure member faces inward of the cavity in the casing 12.

The bottom portion 28 is formed with a passage 32 having the approximate shape of a sector of a circle. It extends over an arc of about 60° at the rim of the bottom portion 28, and tapers in a radially inward direction. An axial slot 34 in the wall portion 30 communicates with the passage 32. A knob 36 rotatably secures the closure member 26 on the cover 14, and permits the closure member to be turned by hand.

In the position illustrated in FIGS. 1 and 2, the closure member is positioned in such a manner that the passage 32 registers with the external orifice of the cut-out 18, and the slot 34 registers with the corresponding orifice of the apertures 16, thus connecting the casing cavity to the ambient atmosphere, and opening a path for the entry of the tool bit 22 into the cavity of the casing 12 for grinding on a radial face of the wheel 10. The arcuate slot 20 is blocked by an imperforate part of the bottom portion 28.

When it is desired to dress the grinding wheel 10, the knob 36 is turned until the imperforate part of the cylindrical wall portion 30 blocks the aperture 16, and a corresponding part of the bottom portion blocks the cut-out 18, while the passage 32 is aligned with the arcuately elongated slot 20 for axial entry of a dressing tool. The dressing tool is mounted on the arm 24, and introduced through the slot 20 by axial and pivoting movement of the pin 21. It is then pivoted back and forth about the axis of the pin 21 to dress the radial face of the wheel 10.

A change from the position of the grinding apparatus illustrated in FIGS. 1 and 2 to that shown in FIGS. 4 and 5 requires rotation of the knob 36 through an angle of approximately 90°, and cooperating abutment means may be provided on the knob and on the cover 14 to limit movement of the closure member accordingly.

While the grinding apparatus of the invention provides different and circumferentially spaced apertures for insertion of a work piece to be ground and of a dressing tool, dust cannot escape and air cannot be drawn into the casing in significant amounts through one aperture while the other one is being used.

Various modifications are contemplated and may obviously be resorted to by those skilled in the art without departing from the spirit and scope of the invention as

hereinafter defined by the appended claims, as only a preferred embodiment thereof has been disclosed.

What is claimed is:

1. In a grinding apparatus, in combination:

- (a) a casing having an axis and defining a substantially closed cavity about said axis, said casing being formed with two spaced passages connecting said cavity with the ambient atmosphere; 5
- (b) an abrasive grinding member rotatable about said axis in said cavity;
- (c) closure means mounted on said casing and movable between a first operative position in which one of said passages is blocked by said closure means while the other passage communicates with the atmosphere, and a second operative position in which said other passage is blocked by said closure means and said one passage communicates with the atmosphere; and
- (d) exhaust means communicating with said cavity for withdrawing air and dust therefrom.

2. In an apparatus as set forth in claim 1, said closure means including a closure member rotatable about said axis between said operative positions, said closure member being formed with an aperture therein positioned for registering alignment with a respective passage in each of said positions.

3. In an apparatus as set forth in claim 2, manually operable means for rotating said closure member about said axis.

4. In a grinding wheel, in combination:

- (a) a casing having an axis and defining a substantially closed cavity about said axis,
- (1) said casing being formed with two passages connecting said cavity with the ambient atmosphere,
- (2) said passages having respective external orifices facing axially and radially relative to said axis;
- (b) an abrasive grinding member rotatable about said axis in said cavity; and
- (c) a cup-shaped closure member mounted on said casing for rotation about said axis between a first operative position in which one of said passages is blocked by said closure member while the other pas-

sage communicates with said atmosphere, and a second operative position in which said other passage is blocked by said closure means and said one passage communicates with the atmosphere,

- (1) said closure member having respective wall portions extending in a radial plane relative to said axis in a cylindrical surface about said axis,
- (2) said wall portions being formed with contiguous respective apertures jointly alignable with a respective orifice in each of said operative positions.

5. In an apparatus as set forth in claim 4, exhaust means communicating with said cavity for withdrawing air and dust therefrom.

6. In an apparatus as set forth in claim 5, one of said orifices and said contiguously communicating apertures jointly defining an elongated opening when in alignment, a dressing tool carrier mounted on said casing for pivotal movement, and fastening means on said carrier for fastening a grinding wheel dressing tool to said carrier in dressing engagement with said grinding member through said elongated opening, and for movement of said tool longitudinally of said elongated opening and radially with respect to said axes during said pivotal movement of said carrier member.

7. In an apparatus as set forth in claim 6, the other one of said orifices and said contiguously communicating apertures jointly defining another opening when in alignment, and guide means on said casing for guiding a work piece to be ground on said abrasive member inward of said cavity through said other opening.
